UNITED STATES PATENT OFFICE

94,467

DESIGN FOR A COMBINED HANGING FLOWERPOT AND BRACKET THEREFOR

Samuel Cantor, Brooklyn, N. Y.

Application October 8, 1934, Serial No. 53,512

Term of patent 3½ years

To all whom it may concern:

Be it known that I, Samuel Cantor, a citizen of the United States, residing at Brooklyn, in the county of Kings and State of New York, have invented a new, original, and ornamental Design for a Combined Hanging Flower Pot and Bracket Therefor, of which the following is a specification, reference being made to accompanying drawing, forming part thereof.

Figure 1 shows a side elevation of a combined hanging flower pot and bracket therefor.

Figure 2 is an edge view showing the supporting bracket.

I claim:

The ornamental design for a combined hanging flowerpot and bracket therefor substantially as shown.

SAMUEL CANTOR.
